US0D1043007S

(12) **United States Design Patent** (10) **Patent No.:** **US D1,043,007 S**
(45) **Date of Patent:** **** Sep. 17, 2024**

(54) **VACUUM**

(71) Applicant: **BLACK & DECKER INC.**

(72) Inventor: **Chao Lien Liu**, Taichung (TW)

(73) Assignee: **BLACK & DECKER INC.**, New Britain, CT (US)

(**) Term: **15 Years**

(21) Appl. No.: **29/785,122**

(22) Filed: **May 24, 2021**

CLAIM

The ornamental design for a vacuum, as shown and described.

DESCRIPTION

FIG. 1 is a front perspective view of a vacuum according to the invention.

FIG. 2 is a front view of the vacuum of FIG. 1.

FIG. 3 is a rear view of the vacuum of FIG. 1.

FIG. 4 is a right side view of the vacuum of FIG. 1.

FIG. 5 is a left side view of the vacuum of FIG. 1.

FIG. 6 is a top plan view of the vacuum of FIG. 1.

FIG. 7 is a bottom plan view of the vacuum of FIG. 1; and, FIG. 8 is a rear perspective view of the vacuum of FIG. 1. The broken lines shown in the figures illustrate portions of the vacuum and form no part of the claimed design.

1 Claim, 8 Drawing Sheets
